UNITED STATES PATENT OFFICE.

JOHN ROBSON, OF WATERBURY, CONNECTICUT, ASSIGNOR TO THE WATERBURY TOOL COMPANY, OF WATERBURY, CONNECTICUT, A CORPORATION OF CONNECTICUT.

AUTOMATICALLY-CONTROLLED DRIVING MECHANISM FOR TEXTILE MACHINERY OR THE LIKE.

Application filed May 5, 1925. Serial No. 28,044.

It is a common practice in many arts, such, for example, as the textile art or the paper making art, where a web of material is subjected to various treatments, to arrange in tandem, or series, the machines for performing successive operations on the material, and to pass the web directly from one machine to the other. This tandem or series arrangement of the machines possesses the advantage of enabling the material to be fed from one machine to the other without handling, but great difficulty is experienced in controlling the driving mechanisms of the different machines to cause them to operate in properly timed relationship. Many different forms of automatic controls for securing the proper timing of the driving mechanisms of the different machines have been proposed, it being a common practice to provide an excess of the web which is held by a more or less freely mounted roller, in a loop or bight between adjacent or successive machines, and to employ this roller for actuating automatically a suitable control. With these controls a disturbance in the timed relationship of the machines produces a variation in the length of the excess material between the two machines and a corresponding change in the position of the freely mounted roller which is used to govern automatically the actuation of a clutch, or other means, connected with the driving mechanism of one or both of the machines.

As the freely mounted roller is supported by the loop of excess material, the weight of the roller which can be employed is necessarily limited by the character of material being treated and as very light rollers must frequently be used it is very difficult to insure the positive actuation of the automatic control. Consequently it has been a problem to devise a control of this type which would be sufficiently sensitive, yet positive in its operation, and at the same time sturdy in its construction. In addition, a further difficulty has been encountered in providing a control capable of quickly producing the necessary changes in the speed ratios of the successive machines without subjecting the machines to sudden jars, and the material to jerks, such as occur when mechanical clutches are employed.

The principal objects of this invention are to provide, for a plurality of machines, adapted to act successively upon a web of material, a new and improved driving mechanism and an automatic control therefore, which while being extremely sensitive, will be positive in its operation, and sturdy and durable in its construction. 55

A further object is to provide such a driving mechanism and control capable of quickly producing the desired speed changes without jerking the material or jarring the machines. 65

These and other objects will appear more fully from the following more detailed description and by reference to the accompanying drawings forming a part hereof. 70

For the purpose of illustration I have shown my invention applied to a tentering machine and drying machine, such as are commonly employed in the textile industry, but it will be understood that the invention 75 is applicable to any machines used for successively treating or operating on material in web form.

In the drawings Fig. 1 is a side elevation of the front or inlet end of a tentering machine having a battery of drying rolls or "cans" mounted in advance thereof; Fig. 2 is a side elevation of the rear or delivery end of the tentering machine; Fig. 3 is a plan view of the structure shown in Fig. 1; Fig. 4 is a transverse detail section on the line 4—4 of Fig. 1; Fig. 5 is a diagrammatic plan on a reduced scale showing an example of the relative location of the main elements of the installation; Fig. 6 is a side elevation partly in section of the fluid pressure pump, and Fig. 7 is a detail section on the line 7—7 of Fig. 6. 80 85 90

Referring to the drawings, the numeral 10 indicates a drying machine consisting of a battery of drying rolls 11, mounted in advance of the inlet end of a tentering machine 12. The web of material 13 to be treated passes to the drying machine and is wound about the rolls 11 thereof from bottom to top, passing from the top roll over an idler 14 and thence downwardly and upwardly about a second idler 14^a to form a loop or bight. A freely mounted roller 15, supported within the said bight, has the ends of its shaft 16 guided for vertical movement in a 100 105

pair of guideways 17 formed in the standards 18. After passing the roller 14^a, the web is trained about the idlers 19, 20, and 21, and is led thereby to the chains 22 of the tentering machine which are provided with means for gripping the cloth in accordance with the usual constructions of devices of this character. After passing from the delivery end of the tentering machine, (shown in Fig. 2), 10 the web may be wound on a roll by any suitable mechanism such as indicated by the numeral 23. The rolls of the drying machine are provided with intermeshing gears, the top roll being provided with a pulley 24 15 adapted to be driven from any source of power, and the tentering machine is provided at its delivery end with a driving gear 25 and a driving pulley for connecting a source of power to the machine.

20 The above construction is that usually employed for machines of this character and various types of speed controls have been used with such machines to secure the driving of the drying rolls and tentering machine in proper timed relationship.

In accordance with the principles of my invention, I employ a fluid pressure driving mechanism comprising a fluid pressure pump A which is driven by any suitable means such 30 as an electric motor 30 and which delivers fluid under a constant pressure to a pair of fluid pressure operated motors B¹, B², connected by the gearing 26 and belt 32, respectively, to the driving mechanism of the tentering machine 12 and drying machine 10. The general construction of the pump and motors is similar, and is of the type disclosed, for instance, in Letters Patent of the United States granted to Harvey D. Williams on June 15, 1909, No. 925,148 and on 40 November 18, 1912, No. 1,044,838. Figs. 6 and 7 illustrate the pump construction. The shaft 35 of the pump is suitably journaled in the pump casing and is connected to the electric motor 30 above referred to. A barrel 36 enclosed within the pump casing is secured to said shaft to rotate therewith, and said barrel has formed therein a plurality of cylinders 37 in which the pistons 38 are 45 adapted to reciprocate. The stroke of these pistons, and consequently the amount of fluid pumped for each rotation of the shaft 35 and barrel 36, depends upon the inclination of the box 39, in which is rotatably mounted a swashplate 40; said swashplate being connected with the pistons 38 by the piston rods 41. As the pistons are caused to reciprocate they suck or force oil through the cylinder ports 42, which are adapted to register alternately, as the barrel 36 rotates, with the arcuate ports 43, 44, formed in the end of the pump casing. One of said ports, for example, the port 43, is the pressure port and the other is the suction port.

55 The pressure port 43 of the pump has con-

nected therewith, the main pressure pipe 45, which connects by the branches 45^a, 45^b, with the motors B¹, and B², while the suction port of the pump has connected therewith, the suction pipe 46 which connects by the 70 branches 46^a, 46^b with said motors. The pump delivers the liquid, (preferably oil), under pressure to the motors through the pipe 45 and branches 45^a, 45^b, and the liquid after passing through the motors, is returned to the suction side of the pump 75 through the pipe 46 and branches 46^a, 46^b. Inasmuch as the construction of the pump and motors is similar, I have deemed it unnecessary to show the internal construction 80 of the motors; it will be understood, however, that the passage of the fluid under pressure through the motors produces the reciprocation of pistons similar to the pistons 38 which causes the rotation of a barrel 85 by means of the connection of said pistons with an inclined rotatably mounted swashplate. It will be further understood that, (as generally the case with pump-motor combinations of this character), the motor boxes 90 corresponding to the pump box 39 are preferably held at a fixed angle, while the inclination of the pump box is variable.

For the purpose of the present invention, I prefer to use a pump having a constant delivery pressure which is maintained by the following mechanism: The box 39 is provided with a lateral projection in the form of a stub axle or pin 50 which is slidably mounted within a spherical bearing 51, movable within a similarly shaped seat in a block 52 formed on the lower end of a rod 53; said block being guided for vertical sliding movement in suitable guideways formed on the inner wall of the pump casing. The upper end of the rod 53 has secured thereto a piston 54 mounted in a cylinder 55 which is connected by the pipe 56 with the pressure port 43 of the pump. The rod 53 extends outwardly beyond the head or end of the cylinder and has secured thereto, a weight carrier 57, adapted to support detachably a plurality of weights 58. Whenever the pump is delivering liquid, the delivery pressure being communicated to the cylinder 55 through the pipe 56 will tend to force the piston 54 upwardly, thus causing the block 52 to move the box 39 and swashplate towards the neutral position, i. e. in parallelism with the shaft 35. The upward force of this pressure will be resisted by the weights 58 and, by properly selecting the amount of weight employed, the position of the swashplate will be varied automatically to maintain the desired constant delivery pressure. In order to compensate for the expansion of the fluid due to increases in temperature the pump and motor casings are connected by the pipes 59 and 60 with an expansion tank 61.

65 As it is the usual practice to operate the 130

tentering machine at a substantially uniform speed, the pressure branch 45^a leading to the motor B¹ is provided with a manually controlled valve 65, which may be set to secure 5 the desired speed of travel of the tenter chains.

The pressure branch 45^b leading to the motor B² for the drying machine is controlled by a valve 66, the opening of which 10 is automatically controlled in the following manner: One end of the shaft 16 of the freely mounted roller 15, has secured thereto one end of a sprocket chain 67 which passes upwardly about the sprocket 68 and 15 thence downwardly, the other end of the chain being secured to the compensating gate or counterweight 69. Sprocket 68 is secured to one end of a shaft 70, the other end of which carries a sprocket 71 which is connected by a chain 72 with a sprocket 73 fixed to the outer end of the stem 74 of the valve 66 which controls the flow of the fluid 20 through the branch 45^b to the motor B².

The operation is as follows: Assuming 25 that the electric motor and pump are placed in operation and the valve 65 is set to secure the desired speed of travel of the tentering machine; if, for example, the speed of the drying machine is too fast, an excess of material 30 will be delivered thereby which will cause the length of the bight or loop in which the roller 15 rests to be increased, and consequently the roller will descend, thus moving the chain 67 and raising the gate 69 35 which will cause the valve 66 to be actuated through the sprocket and chain gearing and throttle the delivery of fluid to the motor B² thereby decreasing the speed of the drying machine. If the drying machine lags behind the tentering machine, the reverse 40 movement of the roller 15, gate, chains and valve will occur thus speeding up the drying machine. Only a very small force is required 45 to move the valve stem 74 but the change of speed of the motor produced by the throttling of the fluid must necessarily be positive, while at the same time because of the well known characteristics of fluid pressure devices, this change of speed is accomplished 50 without any sudden jars or jerks.

It will be understood that many changes, variations and modifications of the construction herein described and illustrated may be resorted to without departing from the spirit of my invention, for example, any 55 number of successive machines may be employed, each having its fluid pressure motor with a common pump.

Furthermore, it will be understood that 60 the invention is not limited in its application to machines of the construction herein disclosed or to machines for performing only drying and tentering operations, but that the invention may be applied to any machines for operating successively on a web of material.

It will also be understood that the invention is not limited in its application to a freely mounted roller for maintaining the excess material between the adjacent machines under tension, as it will be obvious 70 that any suitable means capable of maintaining excess material under tension may be employed and that connections from such means to one of the valves may be used for automatically controlling the flow of fluid 75 to the motor for the machine, the speed ratio of which is to be varied.

I claim:

1. The combination with a plurality of machines for successively treating a web of 80 material and having an excess of said web arranged in a bight or loop between adjacent machines with a freely mounted roller supported within said bight, of a fluid pressure pump and fluid pressure motors actuated by 85 the fluid circulated by said pump, means for connecting one of said fluid pressure motors to each of said adjacent machines, valves for regulating the flow of fluid to said motors, and connections from said freely mounted 90 roller to one of said valves for regulating the speed of the motor controlled thereby in accordance with variations in the position of said roller.

2. The combination with a plurality of 95 machines performing successive operations upon a web of material which is fed directly from one machine to another with an excess of such material between adjacent machines, and means are provided between 100 such adjacent machines for maintaining such excess material under tension, of a plurality of fluid pressure operated motors each operatively connected with the driving mechanism of one of said machines, a fluid pressure pump, conduits connecting said pump and motors, valves for controlling the flow of fluid through said conduits, and an operative connection between 105 said tension maintaining means and one of said valves 110 for automatically controlling the relative driving speeds of said adjacent machines.

3. In an apparatus of the character described comprising a pair of machines for performing successive operations upon a web 115 of material which is fed directly from one of said machines to the other, and movable means for maintaining the material between said machines under tension, characterized by the provision of a fluid pressure operated 120 motor for each of said machines and operatively connected with the driving mechanism of its respective machine, a fluid pressure pump, conduits connected with said pump and motors, valves located in said conduits between the pump and said motors, and operative connections between 125 said means and one of said valves for automatically controlling the flow of the fluid to one of said motors and thereby governing the rela- 130

4
tive driving speeds of said machines in accordance with the movement of said tension maintaining means.

4. In an apparatus of the character described comprising a pair of machines for performing successive operations upon a web of material, a length of which is fed directly from one of said machines to the other, and a freely mounted roller for maintaining said length of material in a loop or bight between said machines, characterized by the provision of a pair of fluid pressure operated motors, one for each of said machines and operatively connected with the driving mechanism 15 of its respective machine, a fluid pressure pump, conduits connecting said pump and motors, valves interposed in said conduits between said pump and motors, and operative connections between one of said valves 20 and said roller for causing said valve to be automatically operated for controlling the speed of said motor in accordance with variations in the length of said loop of material.

5. In an apparatus of the character described comprising a pair of machines for performing successive operations upon a web of material, a length of which is fed directly from one of said machines to the other, and a freely mounted roller for maintaining said length of material in a loop or bight between said machines, characterized by the provision of a pair of fluid pressure operated motors, one for each of said machines and operatively connected with the driving mechanism of its respective machine, a fluid pressure pump, conduits connecting said pump and motors, a counterweight, a chain having its ends connected to said counterweight and freely mounted roller, and a valve interposed in the conduit between one of said motors and said pump, and operatively connected with said chain.

6. An apparatus of the character described comprising a tentering machine and a drying machine arranged in tandem for operating successively upon a web of material, a compensating device interposed between said machines for maintaining the web of material between said machines under tension, a pair of fluid pressure operated motors, one connected to the driving mechanisms of each of said machines, a fluid pressure pump, conduits connecting said pump and motors, a valve interposed between said pump and one of said motors and connections between said valve and compensating device for automatically operating said valve, to regulate the speed of said motor in accordance

with variations in the length of material between said machines.

7. An apparatus of the character described comprising a tentering machine and a drying machine, arranged in tandem for operating successively upon a web of material, a compensating device interposed between said machines for maintaining the web of material between said machines under tension, a pair of fluid pressure operated motors, one connected to the driving mechanisms of each of said machines, a fluid pressure pump, means to insure a constant pressure in the fluid delivered by said pump, suction and delivery conduits connecting said pump and motors, a pair of valves interposed between said pump and motors in said delivery conduits, one of said valves being provided with a manual control to secure a uniform constant speed for one of said motors and connections between the other of said valves and said compensating device to cause said valve to be automatically operated for regulating the speed of the other of said motors in accordance with the movements of said compensating device produced by variations in the length of material between said machines.

8. The combination of a plurality of mechanisms, each having a driving gear and operating successively upon a web of material which is passed in a loop or bight between two adjacent mechanisms and wherein the variation in position of a freely floating roller suspended in said loop or bight is employed to control the relative speeds of said adjacent mechanisms, characterized by the driving gears being of the hydraulic speed gear type supplied with fluid under pressure from a fluid pressure pump, pipe lines connecting said pump with each of said speed gears, a valve in one of said pipe lines, and connections between said valve and said roller to actuate said valve in accordance with variations in the position of said roller, said pipe lines being arranged in parallel whereby when the adjustment of said valve is changed a decrease or increase of the amount of fluid passing through the pipe line controlled by said valve will result in a corresponding increase or decrease respectively of the amount of fluid passing through the pipe line to the other gear thus producing opposite speed changes in said adjacent mechanisms.

In testimony whereof I have hereunto set my hand.

JOHN ROBSON.
